UNITED STATES PATENT OFFICE.

ROBERT LEE GUTHRIE, OF SANTA ROSA, CALIFORNIA.

CULTIVATOR.

1,351,643.

Specification of Letters Patent. Patented Aug. 31, 1920.

Application filed April 29, 1920. Serial No. 377,649.

To all whom it may concern:

Be it known that I, ROBERT L. GUTHRIE, a citizen of the United States, and a resident of Santa Rosa, in the county of Sonoma and State of California, have invented a new and Improved Cultivator, of which the following is a full, clear, and exact description.

This invention relates to improvements in cultivators, and more particularly to hand operated cultivators of the wheel type, an object of the invention being to provide improved means for connecting the standards and braces of the structure to the frame supporting the same, whereby the parts may be easily and quickly adjusted or re-arranged to perform the desired functions.

A further object is to provide an improved cultivator which is adapted to be pulled or pushed over the ground, which can be conveniently transported from place to place, and which will most efficiently perform the functions for which it is intended.

A further object is to improve upon the construction illustrated in my prior application filed November 29, 1919, and given Serial No. 341,353.

With these and other objects in view the invention consists in certain novel features of construction, and combinations and arrangements of parts, as will be more fully hereinafter described and pointed out in the claims.

In the accompanying drawings—

Figure 1 is a view in longitudinal section on the line 1—1 of Fig. 2, illustrating the position of parts when the device is to be pulled over the ground.

Fig. 2 is a top plan view of Fig. 1.

Fig. 3 is a view in longitudinal section on the line 3—3 of Fig. 4, showing the cultivator in position for pushing and also showing a modified arrangement of parts.

Fig. 4 is a top plan view of Fig. 3.

Fig. 5 is a view in section on the line 5—5 of Fig. 6, showing the parts in position for movement from place to place.

Fig. 6 is a top plan view of Fig. 5.

Fig. 7 is a fragmentary perspective view illustrating the manner of supporting one end of the transverse frame bars and the connection of the brace therewith.

Fig. 8 is an enlarged fragmentary view in longitudinal section through the center of one of the standards.

Figs. 9 and 10 are fragmentary views in

elevation at right angles to each other illustrating the manner of connecting one or the braces with the transverse rod.

1, 1, represent a pair of wheels, preferably of relatively large diameter but light in weight. These wheels 1, 1, support an axle 2 and a pair of bracket arms 3, 3, have their forward ends bent forming sleeves 4 receiving the axle 2 and hence, pivotally mounted on the axle.

The bracket arms 3, 3, support a pair of bars 5 and 6. These bars 5 and 6 have trunnions 7 at their ends which are supported on the bracket arms 3, 3, and are held in position on the bracket arms by recessed bearing plates 8 positioned over the trunnions and secured by bolts 9 to the bracket arms 3. This construction and mounting of the bars 5 and 6 permits them to turn or pivot so that they can readily take any angular disposition desired in connection with my improved mounting for the standards 10 and braces 11, as will more fully hereinafter appear.

A pair of handle bars 12 are employed and are connected at their forward ends by a rubber covered handle 13. The rear ends of the bars 12 are connected to the axle 2 by means of collars 14 and 15. In other words, each bar is fixed to a collar 14 and the collars 14 and 15 are connected by rectangular extensions 16, which constitute portions of the handle bars and which extend normally under the bracket arms 3, as clearly shown in Figs. 1 and 2, so that by imparting a pivotal movement to the handle, the plows can be raised and lowered and give the desired elevation. The handle bars 12 are preferably strengthened by a transverse brace rod 17 connecting them.

The standards 10, above referred to, are at their upper portions in the form of relatively flat bars having a longitudinal series of slots 18 therein. The bars 5 and 6 support a series of turn buttons 19, the shanks 20 of these turn buttons having rotary mounting in the bars and the elongated heads 21 of said buttons are of such a shape as to be projected through the slots 18 and when turned at right angles to the slots, will rigidly hold the standards against the bars. The lower portions of the standards have laterally and rearwardly projecting wings 22 which are recessed, as shown at 23, for the accommodation of a tubular rod 24.

Each standard 10 is provided with a

holding strip 25 pivotally connected to the wings 22 at its lower end as shown at 26, and adapted to be positioned across the rod 24 to hold the latter in the recess 23, or, in other words, couple the lower end of the standard to the rod. The upper end of this holding strip 25 is secured in place by means of a turn button 27, the shank 28 of which has rotary mounting in a rod 29 secured to the standard.

When the turn button 27 is in one position, the parts can be securely held, and when turned to its releasing position, the strip 25 can be swung downwardly to disconnect the standard from the rod. Any suitable form of plow 30 may be connected to the lower end of the standard.

The standards 10 are removably connected to the rear transverse bar 6 and are strengthened by the braces 11 which connect the rod 24 with the transverse bar 5. These braces 11 are in the form of relatively flat strips or bars having a longitudinal series of slots 32 to receive in any of them the turn buttons 19 on bar 5.

The lower rear ends of the braces 11 are bowed or bent into U-shape, as shown at 33, particular reference being made to Figs. 9 and 10, and holding strips 34 are hingedly connected to the ends of the strip, as shown at 35, and are provided with slots 36 to receive turn buttons 37 on the braces to secure them in position on the rod 24.

It will thus be noted that I employ turn buttons to secure the standards to the bar 6, to secure the braces 11 to the bar 5, to secure the standards 10 and rod 24 together, and to couple the ends of the braces 11 to the rod 24. By reason of this construction, the parts can be easily and quickly connected and disconnected to form any desired assemblage and can be easily adjusted to give the proper angular disposition to the standards in accordance with the work to be done.

In Figs. 1, 2, 5 and 6, I illustrate a single rod 24 extending transversely of the cultivator, while in Figs. 3 and 4, I illustrate a pair of these rods spaced apart at their center, and it is obvious that any desired arrangement of rods and standards can be employed according to the work to be done by the cultivator.

The parts are shown in Figs. 1 and 2 for pulling the cultivator over the ground. Figs. 3 and 4 illustrate the parts reversed when the cultivator is to be pushed over the ground, and Figs. 5 and 6 illustrate the bracket arms 3 and their connected parts thrown forwardly and supported on the handle bars so that the device can be conveniently transported from place to place.

The pivotal mounting of the bars 5 and 6 enables such bars to take any desired angular position so that the standards and the

braces can be connected or assembled in any desired manner without bending either of said parts, and hence, this feature enables an easy adjustment and control of angular disposition of the standard and brace, as may be desired.

Various slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A cultivator, comprising a support, a pair of normally horizontal parallel bars located on the support, one bar in advance of the other, vertical standards having each a series of slots therein, turn buttons on the rear bar located in any of said slots and securing the standards to the bar, and braces connecting the lower portions of the standards with the forward bar.

2. A cultivator, comprising a support, a pair of normally horizontal parallel bars located on the support, one bar in advance of the other, vertical standards having each a series of slots therein, turn buttons on the rear bar located in any of said slots and securing the standards to the bar, braces connecting the lower portions of the standards with the forward bar, said braces having each a series of slots therein, and turn buttons on the forward bar positioned in the slots of the braces.

3. A cultivator, comprising a pair of wheels, an axle supported by the wheels, bracket arms pivotally connected to the axle, a pair of transverse bars supported by the bracket arms, standards, a transverse rod connecting the lower portions of the standards, braces connected to the rod, and turn buttons adjustably connecting the standards to one of said transverse bars and the braces to the other of said transverse bars.

4. A cultivator, comprising a pair of wheels, an axle supported by the wheels, bracket arms pivotally connected to the axle, a pair of transverse bars supported by the bracket arms, standards, a transverse rod connecting the lower portions of the standards, braces connected to the rod, said standards and braces at their upper ends having a longitudinal series of slots therein, and turn buttons on the respective transverse bars adapted to be located in any of the slots of the braces and the standards respectively.

5. A cultivator, comprising a pair of wheels, an axle supported by the wheels, bracket arms pivotally connected to the axle, a pair of transverse bars having pivotal or rotary mounting in the bracket arms, stand-

ards adjustably connected to the rear of said bars, a rod connecting the lower portions of the standards, and braces connecting the rod with the forward of said pair of transverse bars.

5 6. A cultivator, comprising a pair of wheels, an axle supported by the wheels, bracket arms pivotally connected to the axle, a pair of transverse bars having pivotal or 10 rotary mounting in the bracket arms, standards adjustably connected to the rear of said bars, a rod connecting the lower portions of the standards, braces connecting the rod with the forward of said pair of transverse 15 bars, connecting means between said transverse bars, and the standards and braces comprising turn buttons on the bars located in the slotted portions of the braces and the standards.

20 7. A cultivator, comprising a pair of wheels, an axle supported in the wheels, bracket arms projecting from the axle, transverse bars supported in the bracket arms, standards adjustably connected to the 25 rear of said transverse bars, said standards at their lower portions having wings disposed at an angle to each other, said wings having recesses therein receiving the rod, strips hingedly connected to the wings and 30 positioned across the rod, and means con-

necting the free ends of said strips to the standards.

8. A cultivator, comprising a pair of wheels, an axle supported in the wheels, bracket arms projecting from the axle, 35 transverse bars supported in the bracket arms, standards adjustably connected to the rear of said transverse bars, a rod connecting the lower portions of the standards, said standards at their lower portions having 40 wings disposed at an angle to each other, said wings having recesses therein receiving the rod, strips hingedly connected to the wings and positioned across the rod, turn buttons removably connecting the free ends 45 of said strips to the standards, and braces connecting the rod and the forward of said pair of transverse bars.

9. A cultivator, comprising a support, 50 transverse bars on the support, standards connected to the rear of said transverse bars, braces connected to the forward of said transverse bars, a rod connecting the standards, braces connected to the forward transverse bar, strips hingedly connected to the 55 braces coupling the braces to the rod, and turn buttons locking the strips in operative position.

ROBERT LEE GUTHRIE.
